Primary Examiner — Karen M Redden(74) *Attorney, Agent, or Firm* — Michelle Bos Legal LLC**(57) ABSTRACT**

A new and distinct apple tree named 'PremA025', notable for its resistance to apple scab and for its fruit, which has an attractive red skin color, excellent texture and sweet rich flavor.

3 Drawing Sheets**1**

Latin name: *Malus domestica*.
Variety denomination: PremA025.

BACKGROUND OF THE VARIETY

The new apple tree 'PremA025' was created in the course of a planned breeding program carried out at Havelock North, New Zealand. 'PremA025' originated from a controlled cross made in 1997 of 'Sciros' (seed parent, U.S. Plant Pat. No. 7,814) and 'Pinkie' (pollen parent, not patented). 'PremA025' was selected from a population of seedlings derived from the parents, and was singled out for further observation for its resistance to apple scab, and for its fruit, which has an attractive red skin color, excellent texture and sweet rich flavor. The variety was first asexually propagated by grafting at Havelock North, New Zealand in 2004. 'PremA025' trees have been observed over a number of asexually propagated generations, and have been found to remain true to type.

'PremA025' is distinguished from parent varieties 'Sciros' and 'Pinkie' and from similar variety 'Braeburn' (not patented) as set forth in the tables below.

TABLE 1

Comparison of 'PremA025' to 'Sciros'		
Characteristic	'PremA025'	'Sciros'
Fruit size	225 g	275 g
Leaf color	Green 137B	Green 134A

TABLE 2

Comparison of 'PremA025' to 'Pinkie'		
Characteristic	'PremA025'	'Pinkie'
Skin color	Red solid flush	Pink blush on yellow background
Tree habit	Upright-spreading	Upright

2**TABLE 3**

Comparison of 'PremA025' to 'Braeburn'		
Characteristic	'PremA025'	'Braeburn'
Fruit shape	Globose	Ovoid

BRIEF DESCRIPTION OF THE PHOTOGRAPHS

The attached photographs of 6-year-old 'PremA025' trees and their flowers and fruit were taken at Wapato, Wash. during 2022 growing season. The trees were grown on seedling (*Malus domestica*) rootstock.

FIG. 1 shows blossoms and leaves on a 'PremA025' apple tree;

FIG. 2 shows the fruit, branches and leaves of a 'PremA025' apple tree; and,

FIG. 3 shows fruit and leaves on a 'PremA025' apple tree.

DETAILED BOTANICAL DESCRIPTION OF THE VARIETY

The following-detailed botanical description is based on 25 observations of 6-year-old trees during the 2022 growing season at Wapato, Wash. The described trees were grown on seedling (*Malus domestica*) rootstock. It should be understood that the characteristics described will vary somewhat depending upon cultural practices and climatic conditions, 30 and will vary with location and season. Quantified measurements are expressed as an average of measurements taken from a number of individual plants of the new variety. The measurements of any individual plant or any group of plants of the new variety may vary from the stated average. All 35 colors are described with reference to The R.H.S. Colour Chart, 4th ed. (Royal Horticultural Society, 2001).

Tree:

Vigor.—Moderate.

Type.—Ramified.

Habit.—Semi-upright.

<i>Height.</i> —3.7 meters.	Stamens:
<i>Spread.</i> —1.2 meters to 1.5 meters.	Quantity.—15 to 20.
<i>Trunk diameter (at 30 cm above the graft).</i> —5 cm.	Length.—10 mm.
<i>Bearing.</i> —On spurs.	<i>Anther color.</i> —Yellow 2B.
<i>Bark texture.</i> —Rough.	<i>Pollen.</i> —Scarce.
<i>Bark color.</i> —Greyed-orange N167A.	<i>Pollen color.</i> —Yellow 2B.
<i>Lenticel length.</i> —5 mm.	Pedicel:
<i>Lenticel width.</i> —1 mm.	Length.—3 cm.
<i>Lenticel color.</i> —White NN155B.	Diameter.—1 mm.
<i>Lenticel density.</i> —7 per 10 cm ² .	Color.—Yellow-green 147D.
Branch (fruiting branches located at around 1 m above the graft union):	Sepals:
<i>Length.</i> —55 cm.	Quantity.—5.
<i>Diameter.</i> —6 mm.	Color.—Yellow-green 146D.
<i>Crotch angle.</i> —70°.	Shape.—Lanceolate.
<i>Bark color.</i> —Greyed-orange 177B.	<i>Apex shape.</i> —Aristulate.
<i>Branch lenticel length.</i> —2 mm.	Margin.—Entire.
<i>Branch lenticel width.</i> —1 mm.	Leaves:
<i>Branch lenticel shape.</i> —Rectangular.	Shape.—Ovate.
<i>Branch lenticel color.</i> —White 155B.	Length.—10 cm.
<i>Branch lenticel density.</i> —8 to 10 per cm ² .	Width.—5 cm.
One year old shoot:	Length/width ratio.—2:1.
<i>Length.</i> —26 cm.	<i>Blade margin.</i> —Serrate.
<i>Diameter.</i> —4 mm.	<i>Apex.</i> —Acuminate.
<i>Color.</i> —Greyed-orange 177B.	<i>Base shape.</i> —Equilateral.
<i>Pubescence.</i> —Present.	<i>Color of upper surface.</i> —Green NN137C.
<i>Internode length.</i> —3 cm to 4 cm.	<i>Color of lower surface.</i> —Green 139C.
<i>Shoot lenticel length.</i> —1 mm.	<i>Attitude in relation to shoot.</i> —Upward.
<i>Shoot lenticel width.</i> —0.5 mm.	Petiole:
<i>Shoot lenticel shape.</i> —Rectangular.	Length.—4 cm.
<i>Shoot lenticel color.</i> —White 155B.	Diameter.—1 mm.
<i>Shoot lenticel density.</i> —6 to 8 per cm ² .	Color.—Yellow-green 145C with green NN137C near base.
Flower buds:	Fruit:
<i>Stage described.</i> —Tight.	Quantity per cluster.—2 (after thinning).
<i>Quantity per spur.</i> —5.	Diameter.—8 cm.
<i>Bud shape.</i> —Oval.	Height.—6 cm.
<i>Apex shape.</i> —Rounded.	Weight.—225 g.
<i>Length.</i> —1 cm.	General shape in profile.—Flat-globose.
<i>Diameter.</i> —0.5 cm.	Position of maximum diameter.—At equator.
<i>Color.</i> —Red-purple 67A with white N155B toward base.	Ribbing.—None.
Flowers:	Crowning at calyx end.—Slight.
<i>Diameter of fully open flower.</i> —45 mm.	Size of eye.—Small.
<i>Relative position of petal margins.</i> —Overlapping.	Aperture of eye.—Open.
<i>Date of first bloom.</i> —Apr. 21 (2022).	Depth of eye basin.—1.4 cm.
<i>Date of full bloom.</i> —Apr. 27 (2022).	Width of eye basin.—2.5 cm.
<i>Pollination requirement.</i> —Pollinator required.	Length of sepal.—6 mm.
Petals:	Bloom of skin.—Present.
<i>Number per flower.</i> —5.	Greasiness of skin.—Present.
<i>Petal shape.</i> —Oval.	Background color of skin.—Yellow-green 150D.
<i>Length.</i> —2 cm.	Amount of over color.—80%.
<i>Width.</i> —1.3 cm.	Over color of skin.—Red 47C to 47D.
<i>Apex shape.</i> —Obtuse.	Intensity of over color.—Moderate.
<i>Base shape.</i> —Cuneate.	Pattern of over color.—Solid flush.
<i>Margin.</i> —Entire, ruffled.	Lenticels.—Pronounced.
<i>Color of upper surface.</i> —White NN155C with red-purple 59D near base.	Amount of russet around stalk cavity.—Abundant.
<i>Color of lower surface.</i> —White NN155C with purple 75B near base.	Amount of russet on cheeks.—Absent.
Pistils:	Area of russet around eye basin.—Sparse.
<i>Length.</i> —1.2 cm.	Length of stalk.—35 mm.
<i>Color.</i> —Yellow-green 145B.	Thickness of stalk.—3 mm.
Stigma:	Depth of stalk cavity.—2 cm.
<i>Diameter.</i> —1 mm.	Width of stalk cavity.—2.5 cm.
<i>Color.</i> —Yellow-green 145C.	Stalk color.—Yellow-green 153C.
	Firmness of flesh.—Firm, 15 lbs.

Flesh texture.—Somewhat coarse.
Juiciness.—Moderate.
Brix.—11° Brix.
Flesh color.—White 155B.
Seeds:
Quantity per fruit.—13.
Shape.—Ovate.
Length.—10 mm.
Width.—5 mm.
Color.—Greyed-orange 166B.

Harvest:
Time for harvest.—About Oct. 5 (2022, Wapato, Wash.).
Number of picks.—One.
5   *Disease and pest resistance*.—Resistant to black spot (apple scab, *Venturia inaequalis*); somewhat resistant to apple mildew (*Podosphaera leucotricha*).
I claim:
10   1. A new and distinct apple tree named 'PremA025', substantially as described and illustrated herein.
